UNITED STATES PATENT OFFICE.

PATRICK F. WHITE, OF WESTERN PORT, MARYLAND, ASSIGNOR OF ONE-HALF
TO JACOB S. JAMESON, OF SAME PLACE.

EXHAUST MECHANISM.

SPECIFICATION forming part of Letters Patent No. 440,525, dated November 11, 1890.

Application filed May 31, 1890. Serial No. 353,767. (No model.)

To all whom it may concern:

Be it known that I, PATRICK F. WHITE, a citizen of the United States, residing at Western Port, in the county of Alleghany and State of Maryland, have invented a new and useful 5 Exhaust Mechanism, of which the following is a specification.

This invention relates to exhaust mechanism adapted especially to be used in connection 10 with locomotive-engines; and it has for its object to provide a device of this class which shall possess superior advantages in point of simplicity, durability, and general efficiency, and by means of which the exhaust which is 15 delivered in the usual manner either into the smoke-stack or into the smoke-box may be controlled so as to regulate the draft.

The invention further has for an object to 20 so construct the device as to cause the exhaust of steam to be accompanied by little or no noise.

With these ends in view the invention consists in the improved construction, arrangement, and combination of parts, which will 25 be hereinafter fully described, and particularly pointed out in the claims.

In the drawings, Figure 1 is a side view of an 30 exhaust mechanism embodying my improvements. Fig. 2 is a vertical sectional view of the same on the line 2 2 in Fig. 1. Fig. 3 is a horizontal sectional view on the line 3 3 in Fig. 1. Fig. 4 is a side view showing the device with the perforated funnel detached. Fig. 5 is a detail side view showing said funnel 35 detached from the exhaust. Fig. 6 is a perspective detail view showing the plug detached. Fig. 7 is a sectional detail view showing the nozzle detached.

Like numerals of reference indicate like 40 parts in all the figures.

1 designates the body or casing of the exhaust, which is tapered upwardly, as shown, and which is provided at its lower end with perforated lugs 2, for connecting it with the 45 exhaust-pipe. The upper end of the tapering casing terminates in a cylindrical portion 3, upon which is slidably mounted a ring 4. The casing of the exhaust is provided with a transverse wall or partition 5, extending from 50 its lower end in an upward direction. The

upper end of said wall is provided with a central screw-threaded recess or socket 6, in which is mounted an upwardly extending screw-threaded rod 7, the upper end of which carries an inverted conical or frustum shaped 55 plug 8, which is adjusted upon said rod and is retained in position by means of a jam-nut 9.

10 designates the nozzle, which consists of a ring having an upwardly and outwardly 60 beveled inner side and provided at its upper edge with the flange 10^a, by means of which it is supported upon the upper edge of the casing. Said nozzle is held in position by means of a set-screw 10^b, enabling the said 65 nozzle to be readily removed and replaced by a larger or smaller one when occasion demands.

The vertically-sliding ring 4 upon the upper end of the casing of the exhaust is provided with upwardly and outwardly extending arms 11, to the upper ends of which is secured an inverted funnel 12, terminating in the upwardly-extending discharge-pipe 13.

The conical plug 8 at the upper end of the 75 rod 7 is provided at its edge with a series of vertical notches 14, of which in the drawings hereto annexed three have been shown.

The funnel 12 or pipe 13 is provided with a corresponding number of inwardly-extending 80 lugs 15, which are V-shaped in cross-section, and which, according to the distance at which they are located above the plug 8, serve to more or less obstruct the passage of steam through the notches 14.

16 designates a funnel-shaped ring provided with perforations 17. This ring is provided at its lower edge with notches 18 to enable it to be placed in position upon the vertically-sliding ring 4, which is provided with outwardly-extending studs 19 to engage the lower edge of the funnel 16, which may thus be retained in position upon the said ring. The notches 18 at the lower edge of the perforated funnel are for the purpose of enabling 95 the funnel to be placed in position upon the ring, said notches admitting of the passage of the studs, when by partially turning the funnel or screen it will be retained in position.

Suitably attached to the casing 1 of the ex- 100

haust is an upwardly-extending arm or bracket 20, to the upper end of which is pivoted a lever 21, having a forked end which straddles the discharge-pipe 15 and is connected 5 pivotally with the latter. The outer end of the lever 21 serves as a handle, by means of which it may be conveniently manipulated. This handle is to have suitable connections to enable it to be operated by the engineer.

10 From the foregoing description, taken in connection with the drawings hereto annexed, the advantages and operation of my invention will be readily understood by those skilled in the art to which it appertains. By adjusting 15 the plug 8 upon the rod 7 the sides of the opening for the escape of steam may be regulated. The steam on escaping between the nozzle and the plug 8 is deflected between the beveled walls of said nozzle and plug in an outward 20 direction against the inverted funnel. A portion of the steam, however, escapes in a direct upward direction through the notches 14 in the plug 8, and the force with which this portion of the steam shall be permitted to 25 escape may be regulated by raising or lowering the ring 4, thus bringing the lugs 15 more or less close to the notches 14 in the plug and at the same time diminishing or increasing the space between the inverted funnel and 30 the conical plug. When the said ring 4 is lowered and the lugs 15 nearly closed, the slots 14 and the space between the inverted funnel and the conical plug is diminished, the steam will escape with great force, and the 35 draft in the furnace will be correspondingly increased, and vice versa. At the same time it will be observed that the actual space for the exhaust of steam—that is to say, the space between the nozzle and the conical 40 plug—is not altered, and the exhaust from the cylinder is therefore in no wise affected by the operation of the device.

I would have it understood that in some cases the funnel-shaped screen may be dispensed with—viz., when my invention is applied to what is known as "high exhaust," where the discharge of the exhaust-steam takes place above the screen, which is usually placed in the smoke-boxes of locomotive-boilers for the purpose of preventing the escape of cinders through the stack. When my invention is applied to low exhausts, however, the said perforated screen will be found to be a valuable part of the invention.

55 I desire it to be understood that this invention may be applied to either single or double exhausts, and I reserve the right to any changes and modifications in the detailed construction thereof which may be resorted 60 to without departing from the spirit of my invention.

Having thus described my invention, I claim—

1. In an exhaust mechanism, the combination 65 of the tapering casing having the central partition, the screw-threaded rod mounted

in the latter, the frustum-shaped plug mounted adjustably upon said rod, a vertically-sliding ring mounted upon the casing and having upwardly and outwardly extending arms, an inverted funnel mounted upon said arms and having the discharge-pipe at its upper end, and the perforated funnel or screen mounted detachably upon the sliding ring, substantially as and for the purpose set forth. 75

2. The combination of the exhaust-casing, a screw-threaded rod mounted in the same, a frustum-shaped plug mounted adjustably upon said rod and having vertical notches, the nozzle mounted upon the upper edge of the casing, a vertically-sliding ring mounted upon the upper end of the casing and having upwardly-extending arms, and an inverted funnel mounted upon said arms and having the discharge-pipe and the inwardly-extending lugs registering with and adapted to partially close the vertical notches in the frustum-shaped plug, substantially as and for the purpose set forth. 80

3. The combination of the tapering casing 90 having a cylindrical portion at its upper end, the ring mounted to slide vertically thereon, the upwardly and outwardly beveled nozzle mounted detachably at the upper end of the casing, the screw-threaded rod mounted in 95 the casing, the frustum-shaped plug mounted adjustably upon said rod and having vertical notches, the arms extending upwardly from the vertically-sliding ring and carrying the inverted funnel having the upward discharge-pipe and the inwardly-extending lugs registering with the vertical notches in the frustum-shaped plug, the perforated funnel mounted detachably upon the vertically-sliding ring, an arm or bracket attached to the 100 casing, and a bifurcated operating-lever connected pivotally with said bracket and with the discharge-pipe, substantially as set forth. 105

4. In an exhaust mechanism, the combination 110 with the casing, of the nozzle consisting of an upwardly and outwardly beveled or flaring ring provided at its upper edge with a flange resting upon the upper edge of the casing and a set-screw to retain the said nozzle in position, substantially as set forth. 115

5. In an exhaust mechanism, the combination 120 of the casing having the detachable flaring nozzle, the frustum-shaped plug mounted adjustably above said nozzle, and an inverted funnel arranged above the latter 125 and adjustable vertically independently of the adjustment of the plug, substantially as and for the purpose set forth.

6. In an exhaust mechanism, the combination 130 of the casing, the flaring nozzle mounted detachably at the upper end of the latter, an inverted-frustum-shaped plug mounted adjustably above said nozzle and having vertical notches, and an inverted funnel having a discharge-pipe and provided with inwardly-extending lugs registering with the notches in the plug, said funnel being vertically ad-

justable independently of the adjustment of the plug, substantially as set forth.

7. In an exhaust mechanism constructed substantially as described, the combination, 5 with the vertically-sliding ring carrying the inverted funnel and having outwardly-extending studs, of the detachable perforated funnel or screen provided at its lower edge with notches, substantially as and for the 10 purpose set forth.

In testimony that I claim the foregoing as my own I have hereto affixed my signature in presence of two witnesses.
